FORGING MACHINE

Charles Clausen, Detroit, Mich., assignor to
Standard Forge Company, Detroit, Mich., a
corporation of Michigan

Application March 23, 1936, Serial No. 70,292

5 Claims.

(Cl. 219—3)

This invention relates to a forging machine and more particularly to a machine embodying die blocks for hot forging operations, and an object is to maintain the work at a high temperature, 5 after contact therewith of the dies during the forging operation.

It is also an object to provide electrical means for applying heat to the work and dies during the forging operation, and to provide means whereby 10 the heating current is automatically applied by the movement of a die into contact with the work.

It is also an object to provide certain other new and useful features, all as hereinafter set forth, reference being had to the accompanying drawing, wherein:

Figure 1 is a central vertical section through the die blocks and adjacent parts of a machine illustrative of an embodiment of the present invention;

20 Fig. 2 is a horizontal section upon the line 2—2 of Fig. 1, and

Fig. 3 is a view drawn to a reduced scale showing the complete machine in side elevation and a wiring diagram in connection therewith.

25 In the operation of forging hot metal in dies, the billet which is heated to a very high degree, cools very rapidly upon contact of the die or dies therewith, thus interfering with the forging operation and affecting the granular structure of 30 the forging due to such cooling before the forging operation is completed and the maintaining of the billet at a substantially uniform temperature is therefore essential to secure the best results.

In Fig. 3, a forging machine of a certain construction is shown, but it will be understood that the same is merely illustrative of one form suitable for the purpose, and that the present invention may be applied to any well known forging machine embodying dies of suitable form to give 40 the work the desired shape, upon the application of power in any desired manner to move the dies relatively toward and from each other, and form the work therebetween. In this Fig. 3, 1 indicates a heavy frame having side legs connected at 45 their upper ends by a fluid cylinder 2 and forming an arch, there being a piston 3 in said cylinder having a heavy piston rod 4 projecting from its lower end and formed with a head 5 on its lower end to the underside of which is bolted a 50 second head 6 by bolts 7 with an insulating material 8 between said heads and between said bolts and head 6 to completely insulate electrically, said head from the rest of the machine.

On the lower side of the head or disk 6, said 55 head is formed with an axial hub or boss 9, to the

end face of which hub is bolted a disk 10 having an axial hole to receive a punch pin 11 having a head on its upper end within a recess in the end of the boss, and thus said punch extends downwardly at the axis of said boss to engage within 5 an axial opening in an upper or movable die block 12 which is attached to opposite sides of the hub or boss 9, by brackets 13 bolted at their lower ends to the upper side of said block and connected adjacent their upper ends to said hub by studs 14 10 on said bracket arms projecting into slots 15 formed in the sides of said hub. The die block 12 is thus suspended from the hub 9 of the head 6 to be raised or lowered with the head 5 as the piston 3 is moved in its cylinder, said die block 15 having lost motion relative to said head due to said pin and slot connection of said brackets 13 to said hub. This lost motion permits the block to drop away from the hub so that the lower end of the punch 11 will lie within its opening in the 20 block and just above a recess 16 which forms a continuation of said opening and opens through a boss 17 on the bottom of said block.

The upward movement of the head 6 is limited by means of brackets 18 bolted at their lower ends 25 to the bed or base of the machine at opposite sides of the die block 12 and have upper ends projecting over the periphery of said block. Inside of these brackets directly beneath said block is a lower or fixed die block 19 rigidly secured to the 30 base or bed of the machine by long bolts 20 passing through openings in the block and into the base, said bolts and blocks being electrically insulated as at 21, one from the other and from said base. Said fixed die 19 is formed with a recess 35 22 in its upper side to receive the boss 17 on the upper movable die and a second recess 23 provides the die cavity within which the forging is formed, the same as shown, being in the form of a disk with an axial hub at its lower side, this hub being 40 formed within an axial opening through the block and above a plug 24 in the opening, and 25 indicates the hot billet of cylindrical form set on end upon the upper end of the plug 24 with its upper end directly below the recess 16 in the movable 45 die so that upon descent of the upper block 12, the billet will first come into contact with the upper die by entering said recess, and as pressure is applied, the die will move up until it strikes the lower end of the hub 9, the punch 11 50 simultaneously moving down through the block into contact with the billet. The shape of the dies will of course, be changed according to the shape of the article to be forged, but it is preferable to bring the dies into direct contact with the 55

work in a manner to create a momentary dwell just as contact is made, this being effected by the lost motion between die block 12 and the hub 9 of the head 6.

As soon as the hot billet is put in place, it begins to cool very rapidly particularly as soon as the upper die contacts therewith, and to counteract such cooling, an electric circuit is set up through the two die blocks, one wire of the circuit being secured at 28 to the head 6 of the machine which head is insulated from the rest of the machine, and the other wire is attached at 27 to the fixed block 19 which is also insulated from the remainder of the machine. As long as the die blocks are separated and not in contact with interposed work, no current will flow but just as soon as the upper die descends into contact with the billet, a current of high amperage will flow from one block to the other through the work which is of comparatively small area, and the billet will be immediately heated sufficiently to maintain it at the proper forging temperature.

To obtain such a current of high amperage and low voltage, a transformer is introduced into the current flow from the main supply line indicated at 25, the primary circuit 29 including the usual primary coil 30, an automatic switch 31 and any suitable circuit breaker switch 32 operated by up and down movement of the head 5 or other part of the machine movable with the upper die. Current flow through the primary coil induces current flow in the secondary coil 33 and secondary circuit 34 which includes the die block 19 and head 6 to which the terminals 27 and 28 respectively, of this circuit are connected.

The upper or movable die 12 is moved by fluid pressure entering the opposite ends of the cylinder 2 and controlled by a suitable reversing valve 35 in the supply line 36.

In operation, after placing the billet 25 upon the lower die 19 beneath the upper die 12, the valve 35 is operated to cause the upper die to descend, first bringing it into contact with the upper end of the billet, thereby closing the secondary circuit 34 and simultaneously therewith, operating the switch 32 to close the primary circuit 29. This first contact of upper die with the work thus effects a rapid heating of the work due to the difference in areas of die and work, and this heating is continued until the forging operation is completed and movement of the upper die is reversed, this up movement breaking the circuit as the die leaves the work, and by a further up movement, the switch 32 is opened. By this arrangement, the work is heated throughout the forging operation, sufficiently to prevent undesirable cooling and the operation is facilitated and better forgings secured.

Obviously any suitable construction of forging machine proper, may be employed and other forms of electrical heating and control means may be used without departing from the spirit of the present invention, and such changes are contemplated.

Having thus described my invention what I claim is:

1. In a forging machine, wherein opposing die members are relatively movable into engagement with a preheated blank, made operative to shape the engaged blank into desired form by pressure applied to one of said members and thereafter moved relatively in the opposite direction to release the shaped and formed product, said machine including means for moving said members relatively with a dwell in said movement into en-

gagement with the blank interposed therebetween, and an electric heating circuit within which said members are connected and which circuit is closed by the bringing of one of said members into contact with said blank to reheat the latter through substantially its entire length during said dwell. 5

2. In a forging machine, wherein opposing die members are relatively movable into engagement with a preheated blank, made operative to shape the engaged blank into desired form by pressure applied to one of said members and thereafter moved relatively in the opposite direction to release the shaped and formed product, said machine including means for electrically insulating each of said members from other parts of said machine, said members each comprising an electrode, a heating electric circuit within which circuit said members are connected for completing the circuit through said members and said blank by the movement of one of said members into contact with said blank, and means for moving said members with a dwell in said movement upon contact between said blank and members and the closing of said circuit. 10 15 20 25

3. In a forging machine, wherein opposing die members are relatively movable into engagement with a preheated blank, made operative to shape the engaged blank into desired form by pressure applied to one of said members and thereafter moved relatively in the opposite direction to release the shaped and formed product, said machine including means for moving said members relatively with a dwell in said movement into engagement with the blank interposed between said members, an electric circuit the terminals of which are electrically connected to said members, said members being separately insulated from the other parts of said machine, and said circuit through said members and blank being completed by a movement of one of said members into contact with said blank and adapted for substantially constant and uniform heating of said blank during said dwell and said forging operation. 30 35 40 45

4. In a forging machine, wherein opposing die members are relatively movable into engagement with a preheated blank, made operative to shape the engaged blank into desired form by pressure applied to one of said members and thereafter moved relatively in the opposite direction to release the shaped and formed product, said machine including a fixed die and a movable die each being separately insulated from the other parts of said machine, each of said dies comprising an electrode, means for moving said movable die with a dwell in its movement toward and away from said fixed die, said blank being supported by but separate from one of said dies, an electric heating circuit within which said dies are connected for heating said blank, said circuit including primary and secondary windings to be closed by the contact between said blank and one of said dies for uniformly heating said blank during said dwell, means within said primary circuit for closing said circuit, and a switch controlling said means engageably operable with the movement of said movable die. 50 55 60 65 70

5. A forging machine including a fixed die, a movable die in opposed relation to said fixed die, a movable carrier member upon which said movable die is mounted for movement relative to said carrier, power means for moving said movable die and carrier toward said fixed die to forge work interposed between said dies, said move- 75

ment of said movable die relative to said carrier providing lost motion in the movement of said movable die toward said fixed die when said movable die comes into contact with work interposed between said dies, means for insulating each of said dies from their supports, a heating circuit including a primary and a secondary, said secondary circuit including said dies and adapted

to be closed by a movement of the movable die into contact with the work and to be opened by a movement of said die out of contact with the work, and a switch device operated by a movement of the movable die out of contact with the work, to open said primary circuit. 5

CHARLES CLAUSEN.
